UNITED STATES PATENT OFFICE.

THEODORE H. BROWN AND HOUGHTON BROWN, OF MINNEAPOLIS, MINNESOTA,
ASSIGNORS OF ONE-HALF TO JAMES R. STEWART, OF MINNEAPOLIS, MINNESOTA.

BROOM.

1,174,013.

Specification of Letters Patent. Patented Feb. 29, 1916.

Application filed November 18, 1915. Serial No. 62,139.

To all whom it may concern:

Be it known that we, THEODORE H. BROWN and HOUGHTON BROWN, citizens of the United States, residents of Minneapolis, county 5 of Hennepin, State of Minnesota, have invented certain new and useful Improvements in Brooms, of which the following is a specification.

The object of our invention is to cheapen 10 the cost of manufacture of a broom and at the same time add to its strength and durability.

A further object is to provide a broom in which the use of wire for lacing the head 15 of the broom is entirely dispensed with.

The invention consists generally in various constructions and combinations, all as hereinafter described and particularly pointed out in the claims.

20 In the accompanying drawings forming part of this specification, Figure 1 is a plan view of the blank from which the cap for the head of the broom is formed, Fig. 2 is a similar view, showing the cap in its unfolded position, with the broom corn and the stick laid therein, Fig. 3 is a view showing the cap folded around the corn and secured, Fig. 4 is a similar view of the opposite side of the broom.

30 In the drawing, 2 represents a panel of the blank on one side of the cap and 3 end flaps which are folded along the lines 4 and 5 around the edges of the broom. The blank on each side of the panel is provided with 35 diagonal slits 6 and 7 arranged in pairs and converging toward one another and intersecting the folds 4 and 5, forming wings 8 on each side of the middle panel. These wings are each recessed at 9 to fit 40 around the stick 10 that is placed between them.

11 represents a bundle of broom corn that is spread out flat, smeared with a preparation of asphalt and laid upon the panel 45 2, as the first step in the operation of making the broom. The stick is then placed upon the broom corn centrally with respect to the blank and the ends of the blank are then folded over upon one another 50 around the broom corn and drawn up sufficiently to grip the corn firmly. The overlapping sections 3 are then secured together

by a suitable means, such as nails 12, driven through them and into the broom stick, and the wings 8 are wrapped snugly around the 55 head of the broom and secured in a similar manner. When these overlapping parts of the blank have all been firmly secured, the broom is complete and ready for use, all without the use of the lacing wires usually employed in broom construction.

We prefer to provide a metallic cap 13 on the end of the stick, covering the joint between the fiber wings and the surface of the stick. We also prefer to pass rivets 65 through the lower portion of the fiber cap which encircles the head of the broom for binding it and the corn securely together. These rivets are preferably below the end of the stick and substantially in line therewith.

The blank may be made of suitable material, but preferably of a vulcanized fiber of suitable gage, capable of being folded to the desired form and being extremely 75 tough and tenacious, which will allow comparatively short bends to be formed therein without breaking or cracking and will also have sufficient body to retain the nails or other fastening means which may be driven 80 therethrough.

We have found the asphaltum particularly suitable as a binder for the broom corn, but do not confine ourselves to such material, as any other substance having a similar function may be employed, if preferred.

We claim as our invention:

1. A broom having a stick and a supply of broom corn having a suitable binder, a cap encircling one end of the stick and the 90 corn and composed of a panel forming one side of the cap, and flaps adapted to be folded around the edges of the broom head and lapping by one another, said cap also having wings formed thereon fitting snugly 95 around the broom stick and covering the head of the broom at its junction with the stick and means for securing said cap to the broom.

2. A cap for a broom having a stick, 100 formed from a blank of suitable material having a central panel and flaps provided on each side of said panel, said blank having converging slits at one end of said panel and

between it and said flaps forming a pair of wings, said panel forming one side of the broom cap and said flaps being folded around the edges of the broom to form the cap on the other side thereof and having their overlapping edges secured together, said wings being folded around the head of the broom and the stick and having

means for securing their overlapping edges together.

In witness whereof, we have hereunto set our hands this 3rd day of November, 1915.

THEODORE H. BROWN.
HOUGHTON BROWN.
